UNITED STATES PATENT OFFICE.

HENRY T. POPE AND BENJAMIN F. KIDDER, OF FORT PAYNE, ALABAMA.

DESIGN FOR A JUG.

SPECIFICATION forming part of Design No. 27,859, dated November 16, 1897.

Application filed October 6, 1897. Serial No. 654,299. Term of patent 7 years.

To all whom it may concern:

Be it known that we, HENRY T. POPE and BENJAMIN F. KIDDER, citizens of the United States, residing at Fort Payne, in the county of De Kalb and State of Alabama, have invented and produced a new and original Design for a Jug, of which the following is a specification, reference being had to the accompanying drawings, forming a part thereof, in

10 which—

Figure 1 is a perspective view of a jug embodying the features of our design, and Fig. 2 is a vertical central section through said jug.

15 The features of the design consist in a cylindrical body A, having a central horizontally-embossed belt B, and especially in the formation of the upper portion of the jug,

wherein a decided annular depression or well C appears, having a dome-shaped bottom D 20 and a tapering tubular crowning ornament E.

At opposite sides of the upper portion of the jug fins F are formed, which conform to the vertical surface contour of the jug and terminate near the margin of said depression 25 C. The bottom of the jug arches in an upwardly direction.

We claim—

The design for a jug herein shown and described.

HENRY T. POPE.
BENJAMIN F. KIDDER.
